DECORATIVE SCREEN

Jeanne L. Adams, Vashon, Wash.

Application May 7, 1954, Serial No. 30,372

Term of patent 3½ years

(Cl. D29—1)

Fig. 1

To all whom it may concern:

Be it known that I, Jeanne L. Adams, a citizen of the United States, residing at Vashon, in the county of King, State of Washington, have invented a new, original, and ornamental Design for a Decorative Screen, of which the following is a specification, reference being had to the accompanying drawings, forming a part thereof.

Fig. 1 is a front elevation view of a decorative screen showing a new design.

Fig. 2 is a top plan view thereof.

I claim:

The ornamental design for a decorative screen, as shown.
